[57] **CLAIM**

The ornamental design for a kite or similar article, substantially as shown and described.

DESCRIPTION

FIG. 1 is a perspective view of a kite showing my new design with one wing rotated to a substantially vertical position and the other rotated to a substantially horizontal position;

FIG. 2 is a top plan view thereof on a smaller scale with both wings disposed in a horizontal position;

FIG. 3 is a front elevational view thereof on a larger scale than FIG. 2 with both wings disposed in a vertical position;

FIG. 4 is a side elevational view thereof on approximately the same scale as FIG. 1 with the wings shown in a substantially horizontal position;

FIG. 5 is a bottom plan view thereof with the wings disposed as in FIG. 2 and on the same scale;

FIG. 6 is a rear elevational view thereof with the wings disposed as in FIG. 3 and on the same scale; and

FIG. 7 is a cross-sectional view of the wing member taken on the line 7—7 of FIG. 5, but on a larger scale.
